DRAFTING APPARATUS

Charles Hubbard Little, Pepper Pike, Ohio, assignor to Universal Drafting Machine Corporation, Cleveland, Ohio, a corporation of Ohio

Filed Feb. 9, 1959, Ser. No. 792,075

19 Claims. (Cl. 33—76)

The present invention relates to so-called "drafting machines" and more particularly to drafting machines having one or more straight edges, rulers, triangles, etc., connected to a member movable upon a linear track.

In the machines of the character referred to, the ruler or rulers, etc., are usually pivotally connected to the member, which member is in turn movable upon the linear track and the member which provides the track is in turn movable upon a second linear track positioned at right angles to the first.

One of the principal objects of the invention is the provision of a new and novel drafting machine or like apparatus of the character referred to which will be simple, stable and rugged in construction and therefore accurate in operation, economical to manufacture and maintain, and low in friction, light in weight and therefore extremely easy to operate.

Another object of the invention is the provision of a new and novel drafting machine or like device of the character mentioned, which can be readily manufactured for use with boards of any practical size and in which machine there will be a minimum of deflection and sag although the rail members are supported at only two points.

Another object of the invention is the provision of a new and novel drafting machine or like device comprising an "X" or "Y" beam or rail having a relatively narrow centrally located track along which the "carriage" moves and wherein the track proper is enclosed and thus protected against dirt, damage, etc.

Another object of the invention is the provision of a new and novel drafting or like device of the character referred to having a counterweight movably supported in the "Y" beam or rail and connected to the carriage movable along the rail or track to provide proper balance at all board angles automatically and which does not overhang the board and is completely out of the way at all times.

The invention resides in certain novel constructions and arrangements of parts, and further objects and advantages will appear from the following description of the preferred embodiment described with reference to the accompanying drawings, which form a part of this specification, and in which like reference characters designate corresponding parts throughout the several views, and wherein:

FIG. 1 is a fragmentary plan view of a drafting table or board having a drafting machine embodying the present invention attached thereto;

FIG. 2 is an enlarged fragmentary plan view with portions broken away and in section of the drafting machine shown in FIG. 1;

FIG. 3 is a sectional view with portions in elevation approximately on the line 3—3 of FIG. 2;

FIG. 4 is an enlarged sectional view with portions in elevation approximately on the line 4—4 of FIG. 3;

FIG. 5 is an enlarged sectional view with portions in elevation approximately on the line 5—5 of FIG. 2;

FIG. 6 is an enlarged sectional view with portions in elevation approximately on the line 6—6 of FIG. 2; and

FIG. 7 is a fragmentary sectional view approximately on the line 7—7 of FIG. 2.

Although the preferred embodiment of the invention is herein shown and described in detail, it is to be under-

2

stood that the invention is not limited to the constructions and arrangements of the parts shown and described, but is capable of being otherwise embodied and of being practiced and carried out in various ways.

Referring to the drawings, the apparatus shown therein comprises a pair of rulers A, B extending at right angles to one another and movable over the working surface of a drafting table or board C. The rulers, commonly called drafting machine scales, are detachably connected to a ruler supporting member D pivotally connected to a protractor assembly or protractor E for movement or adjustment about an axis normal to the surface of the board C. The protractor E comprises a flexible attachment plate or blade which is in turn detachably connected to a "Y" carriage F movable upon a linear "Y" beam or rail G extending downwardly from the upper edge of the board C, as viewed in the drawings at right angles thereto.

The vertical beam G is pivotally connected, for oscillation about an axis generally parallel with the upper edge of the board C, to a second or "X" carriage H movable upon a linear "X" beam or rail J extending generally parallel with the upper edge of the board C and at right angles to the length of the vertical beam G. The beams G, J are preferably made of extruded aluminum alloy and in such a shape that they are extremely resistant to deflection or distortion, etc. in all directions. The horizontal rail beam J is connected to the board C at only two spaced points so that warpage and other distortion of the board C will not be imparted to the beam. With this construction the normal come and go inherent in drafting boards and tables will not be reflected in the horizontal beam J.

The beams G, J are identical in construction and each comprises a length of beam the cross-sectional shape of which is clearly shown in FIG. 3 and which resembles somewhat the shape of a conventional I-beam, in that it has a central web 15 and pairs of flanges 17, 18 and 20, 21 adjacent to opposite longitudinal edges of the web projecting to opposite sides thereof. The beam is symmetrical about its longitudinal, central plan normal to its web, with the result that the flanges on either side of the web are alike. In addition to the edge flanges 17, 18 and 20, 21 each beam has a further longitudinal flange 22 projecting from the top side of the web 15 as viewed in FIG. 3 and located midway between the flanges 17, 20, that is, the edge flanges on the same side of the web as the flange 22. The flange 22 is relatively narrow compared to the width of the beam, being never more than one-half the width of the beam and preferably being about one-eighth the width of the beam as is the case in the embodiment shown. The opposite sides of each of the flanges 22 are accurately machined to provide pairs of longitudinally extending transversely spaced main guide surfaces which form an accurate straight or linear guideway or track along each beam for the carriages.

The carriage F which is generally rectangular as viewed in plan, is guided along the flange 22 of the vertical beam rail G by four wheels or rollers 23, 24, 25, 26 at the under side of the frame member 27 of the carriage and connected to the frame member of the carriage adjacent to the upper and lower ends thereof as viewed in FIG. 2. The wheels or rollers 23, 24, 25, 26 shown are in fact the outer races of anti-friction ball type bearings, the inner races of which are fixedly secured to the lower end of pins or stud shafts 30, 31, 32, 33, respectively, provided with upwardly projecting bosses all of which but one, in this instance the shaft 33, is eccentric to the axis of the respective wheel carried by the shaft.

The shafts 30, 31, 32, 33 are provided with enlarged heads at their lower ends against which the inner race of the bearing which forms the wheel carried thereby en-

gages. The upper reduced ends of the shafts are threaded and project through suitable holes in the frame 27 of the carriage where they are provided with nuts 36 by which the shafts may be fixedly secured to the frame. Suitable washers may be interposed, if desired, between the lower and upper ends of the inner race of each bearing and the head of the shaft and the adjacent portion of the under side of the frame 27. A lock washer is preferably employed underneath the nut 36. A slot in the upper projecting end of the reduced portion of each of the shafts facilitates angular adjustment of the shafts when the respective nut 36 employed therewith loosened.

The fact that the three shafts 30, 31, and 32 are supported by eccentric portions thereof in the frame 27, provides means for adjusting the carriage F and in turn the rulers etc. connected thereto, relative to the guideway for the carriage formed by the opposite sides of the flange 22. In assembling or setting up the device the two shafts 30, 31 at the left hand side of the flange 22 may be adjusted to provide clearance between the wheels carried thereby and the adjoining side of the flange. The shaft 32 may be thereafter adjusted to obtain the desired angular relationship between the carriage and the track and the shafts 30, 31 subsequently adjusted to cause all of the wheels to firmly engage the flange 22. Alternatively, one of the shafts 30, 31 may be omitted and the retained shaft relocated intermediate the shafts 32, 33. The shafts 32, 33 are preferably widely spaced lengthwise of the rail relative to one another so as to provide two relatively widely spaced points of contact with the rail and thereby reducing the tendency of the wheels carried thereby to bind on the track, etc. The spacing should be at least two or more times the width of the flange 22 and in the embodiment shown is approximately ten times the flange width.

The flanges 17 and 20 on the upper sides of the beam which form the vertical beam G have portions 40, 41 turned inwardly to overhang the side edge of the central web 15 adjacent thereto, thereby providing discrete supplemental guide surfaces or guideways along opposite side edges of the beam for a plurality of "outrigger" rollers 42, 43, 44, 45 connected to the frame 27 of the carriage F for rotation about axes parallel to the plane of the web 15. As shown, the rollers 42 to 45 are rotatably connected to outwardly projecting ends of stud shafts fixedly secured in downwardly projecting bosses on the underside of the frame 27 by nuts threaded onto their inwardly projecting ends. The rollers 42 to 45 are located adjacent to the track rollers 23 to 26 respectively and prevent tilting the carriage F relative to the beam or its removal therefrom. In other words, the rollers 42 to 45 maintain the carriage in assembled fixed relationship to the beam while leaving it free to travel lengthwise thereof and be guided therealong by the guideways or tracks formed along opposite sides of the central web 22. The nuts 36, etc., are enclosed in a housing or cover member 46 detachably connected to the frame 27 of the carriage F by suitable screws.

The carriage F is adapted to be locked or clamped in any position to which it is moved along the beam G by lock means including a brake or friction member 50 connected adjacent to the free end of a resilient lever 51 located at the lower side of the frame 27 of the carriage F and detachably connected thereto by screws 52. The friction member 50 normally travels freely in a groove 53 formed in the upper side of the flange 22 but is adapted to be pressed into tight engagement with the bottom of the groove by a screw 54 threaded in a tapped aperture in a boss 55 projecting from the upper side of the frame 27 of the carriage F. The lower end of the screw 54 abuts against the upper side of the member 51 intermediate the ends of the member 50 and its upper end projects outwardly through a suitable aperture in the cover 46 where it is provided with a knurled wheel or knob 56. Rotation of the knob 56 in the clamp direction

will engage the lower surface of the member 50 with the bottom of the groove 53 to lock the carriage F to the beam rail G. Rotation in the opposite direction will allow the member 50 to be moved free of the lower surface of the groove 53 by the resiliency of the member 51 to which it is attached to return the carriage.

The downwardly projecting flanges 13, 21 on the underside of the rail G include outwardly projecting flanges 60, 61 and inwardly projecting flanges 62, 63, respectively. 10 The latter flanges have inwardly facing V-shaped grooves 64, 65 which provide second supplemental guide surfaces forming trackways for wheels 66, 67 connected to and forming a part of a counterweight K used in connection with the vertical rail G. Opposite ends of the counterweight K are connected to opposite ends of the carriage F by web-like flexible bands 68, 69 which are looped or reeved about suitable rolls or pulleys 70, 71 rotatably supported in brackets connected to opposite ends of the beam G. In addition to providing a means for connecting the counterweight K to the carriage F the webs 68, 69 enclose the upper and lower sides of the beam, thereby providing a neat appearance and assisting in preventing the entrance of dirt and other undesirable objects into the top side of the beam where they might interfere with the accurate movement of the carriage along the beam. The projection of the flange 22 from the web 15 is preferably less than the projection of the side flanges 17, 20 which assists in protecting the guideway or tracks thereon from damage etc.

30 From the foregoing description of the manner in which the carriage F is supported and counterbalanced on the beam G it will be evident that friction has been reduced to a minimum and that the carriage is extremely free to be moved along the beam with minimum effort on the part of the operator. This is accomplished in part by the use of flat parallel guideways or tracks on opposite sides of the flange 22 and in part by the use of a narrow flange for the guideway or track relative to the spacing between the upper pair of rollers 23, 26 and the lower pair 24, 25. It will also be noted that the outrigger rollers 42 to 45 are on the centerline of the track and there are no forces between the carriage F and the beam G tending to produce inaccuracies in the apparatus. The fact that the carriage F is well counterbalanced and is freely movable along the beam G makes it easy for the operator to place the carriage F and in turn the rollers carried thereby in any desired position. The configuration of the beam G reduces if not eliminates sag and other distortions even though the beam may be of considerable length.

50 The upper end of the beam G is provided with a bracket 75 detachably connected to its underside by screws 76 threaded into suitable tapped apertures in the outwardly extending flanges 60, 61 of the beam. The bracket 75 has a tubular cylindrical projection 78 at the right-hand side, as viewed in FIG. 2, and an hourglass shaped projection 79 at the left-hand side, which projections pivotally connect the bracket 75 and in turn the vertical beam G to the frame 80 of the carriage H. The projections 78, 79 of bracket 75 engage within suitable apertures in upstanding flanges 81, 82, respectively, of the frame 80 of the "X" carriage H and are retained therein by cover members or hinge straps 83, 84 engaging thereover and detachably connected to the upstanding flanges 81, 82 by suitable screws. The construction is such that the upper end of the beam G is cradled in the horizontal carriage H such that the lower end of the beam G may be raised and lowered to pivot the beam about the axes of the bosses 78, 79. The hourglass shape of the projection 79 prevents axial momentum of the bracket 75 and in turn the upper end of the beam G relative to the carriage H.

75 The carriage H is similar in construction to the carriage F and is connected to the horizontal beam J in a similar manner. The frame 80 of the carriage H is slightly larger and different in certain other respects from the

frame of the carriage F. All material differences will be referred to. As previously stated, the beam J at the upper edge of the board C is similar to the beam G and will not be described in detail. The corresponding parts of the beam J are, however, designated in the drawings and will be referred to herein by the same reference characters employed with respect to the beam G, but having a prime mark affixed thereto. The beam J extends along the upper edge of the board C and is connected thereto at only two points as previously mentioned by two brackets 85, 86 connected to the underside of the board and to the flanges 60', 61' of the beam in a suitable manner.

The frame member 89 of the horizontal carriage H is connected to the beam J in a manner similar to that in which the frame member 27 of the carriage F is connected to the beam G, and will not be described in detail. The corresponding parts, however, are designated in the drawings by the same reference characters as those employed with respect to the carriage F but with a prime mark affixed thereto. Since no counterweight similar to the counterweight K, previously referred to, is required with the horizontal beam J, a single web-like flexible band 90 is employed with the horizontal beam. The band 90 is reeved about suitable pulleys rotatably connected in opposite ends of the beam J and has its opposite ends detachably connected to the frame member 89 of the carriage H.

The carriage H is adapted to be secured or locked in any position along the horizontal beam J by friction members 91, 92, somewhat similar to the friction member 50 previously referred to, connected to the upper side of the free end of flexible resilient members 93, 94 having flanges integral therewith and by which they are detachably connected to the frame member 89 of the horizontal carriage H adjacent to the upper and lower sides thereof by suitable screws. The friction members 91, 92 underlie the inwardly projecting flanges 40', 41', respectively, at the top side of the web 15' of the beam J and are adapted to be moved upwardly into engagement therewith by lever members 95, 96 secured to the outwardly projecting ends of short shafts 100, 101 rotatably supported in downwardly projecting bosses on the underside of the frame member 89. The inner ends of the shafts 100, 101 are connected to downwardly projecting arms of a lever 102, which lever is carried by the shafts 100, 101. The lever 102 has an upwardly projecting arm 103 provided with a pin 104 projecting therefrom in a direction parallel with the axis of the shafts 100, 101. The projecting end of the pin 104 extends into a peripheral groove in a wheel-like member 105 fixedly connected to the end of a member 106 slidably supported in the boss 78 of the bracket 75, previously referred to. A tension spring 110 connected to a projection 111 on the lever 102 and to an upstanding member 112 on the frame member 89 of the carriage H continuously biases the lever in a counter-clockwise direction as viewed in FIG. 5; that is, in a direction to allow the friction members 91, 92 to occupy positions free of the flanges 40', 41', under the resiliency of the members 93, 94. Movement of the lever 102 by the spring 110 is limited by a collar-like spacer 113 interposed on the member 106 between the wheel-like member 105 and the adjacent side of the upstanding part 81 of the frame member 89 within which the boss 78 is rotatably supported.

The member 106 is adapted to be moved toward the right as viewed in FIGS. 2 and 5 to pivot the lever 102 and in turn, the levers 95, 96 in a direction opposite to the action of the spring 110; that is, in a direction to engage the friction members 91, 92 with the flanges 40', 41' by an arcuate shaped member or wedge 115 of gradually increasing width pivotally connected to one end of a walking beam-type lever 116 and having its narrow, free end projecting between the roller 117 carried by the member 106 and a roller 118 connected to the bracket 75. The lever 116 is pivotally connected to the bracket

75 and the construction of the wedge 115, etc., is such that oscillation of the lever 116 will cause the wedge 115, which has a gradually increasing width, to be projected and withdrawn from between the rollers 117, 118, thereby causing the friction members 91, 92 to engage the flanges 40', 41' or to allow them to move away therefrom. The member 106 is held against rotation in the boss 78 by suitable flanges on the wheel 117.

Provision is made for oscillating the lever 116 about its pivotal connection to the bracket 75 in the form of a rod 120 located in an outwardly facing groove in the vertical beam G formed by the flanges 20, 21. The rod 120 extends from a point adjacent to the upper end of the beam G to a point near the lower end of the beam and is slidably connected to the beam G by suitable spaced brackets 121 positioned at desired locations along the left-hand side of the vertical beam G, as viewed in FIGS. 1, 2, 4 and 7. The upper end of the rod 120 is connected to the end of the lever 116 opposite to the end to which the lever 115 is connected by a pin 122 fixed in the rod 120 and engaging within a slot 123 in the lever 116. The lower end of the lever 116 is provided with a grasp 126 projecting outwardly from the left-hand side of the vertical beam G. The grasp 126 is located at a convenient position along the vertical beam G and facilitates the convenient clamping and unclamping of the horizontal carriage F with respect to the beam J. Two brackets 121 located at opposite sides of the grasp 126 form stops which limit movement of the rod 120 along the beam G. One of the advantages of the mechanism just described for locking the horizontally movable carriage H to the horizontal beam J is the fact that the vertical beam G can be disconnected from and reconnected to the carriage H by merely removing and replacing the members 33, 34 which overlie the projections 78, 75 of the carriage frame member 89.

In the particular apparatus shown in FIG. 1, the lower edge of the drafting board or table C is provided with a longitudinally extending metal bar-like member 130, preferably made of extruded aluminum which forms a guide-way for rollers, not shown, connected to the bracket at the lower end of the vertical beam G which supports the pulley 70. This facilitates movement of the vertical beam G relative to the board C.

The rulers A, B, the ruler supporting member D, and the protractor E form an assembly, commonly referred to as a drafting machine head, which is detachably connected to the "Y" carriage F and may be removed as a unit. The particular drafting machine head shown, per se, forms no part of the present invention and can be replaced by any desired different drafting machine head. The head shown is commercially available and is shown in U.S. patent to Charles Hubbard Little et al., No. 2,552,335, where it is shown connected to the free end of a band type parallel motion arm. In order to facilitate or to assure that the rulers A, B, or whatever other instruments are connected to the vertically movable carriage F, will lie flat on the board C, the attachment means for connecting the assembly E to the frame member 27 of the carriage F is preferably flexible in the plane of the board. In the embodiment shown this means is in the form of a plate or blade 131 having two slots within which two screws carried by the frame 27 of the carriage F engage to detachably secure the drafting machine head E to the carriage. The screws project upwardly through the frame 27 and are provided with wing nuts 132, 133 to facilitate detaching the drafting machine head being used at any particular time.

As will be readily appreciated, the scales A, B are of limited length, usually 12 to 18 inches, and in order to facilitate the making of large layout drawings, etc., with no accumulative error due to repeated scale extensions, etc. the present invention provides a plurality of track settings along both the "X" and "Y" beams in the form of graduations 140, 141 along the inner beveled edges

7
of the rail beams G and J, respectively. In the embodiment shown, these graduations are at ten inch intervals and the respective carriers are adapted to be accurately positioned with respect thereto by indicator members 142, 143 connected to the carriages F and H, respectively. Each of the indicator members has a V-shaped notch in the portion thereof which projects over the graduations with which it cooperates, which notch is preferably three times as wide as the width of the graduations. This construction provides a simple mechanical device for increasing the reading sensitivity of the indicator and the graduations by a ratio of approximately 3½ to 1. In setting the respective carriages the apex of the V-notch in the indicator connected thereto is brought over the beam graduation and positioned so that the two triangles formed by 10 the notch and the graduation on either side of the graduation appear equal to the eye. In this way, a setting can be made repeatedly to less than .010 of an inch. The beam graduations in effect divide the drafting board into a grid pattern which, in the preferred embodiment shown, 15 is a ten inch pattern. With this construction, different parts of a drawing can be worked upon with complete confidence in the accuracy of one part relative to another, regardless of the size of the drawing, since widely separated reference points can be established with no accumulative error. 20

25 From the foregoing description of the preferred embodiment of the invention, it is believed that it will be apparent that the objects heretofore enumerated and others have been accomplished and that there has been provided a new and novel drafting apparatus of the character described which is economical to manufacture, is rugged in construction and which will maintain its accuracy under all normal uses. The fact that the rail members are quite 30 wide and have the characteristics of an I-beam assures against their distorting in use and the fact that the guide surfaces for the respective carriages are relatively close together with respect to the distance between the guide or track wheels at opposite ends of the carriages assures 35 their free and accurate movement along their respective tracks.

40 As previously stated, the rail beams have a cross sectional configuration which provides extreme rigidity and lack of deflection in all directions while being relatively light in weight. The side flanges projecting in opposite directions from the side edges of the web of the beam provide stability against deflection of the rail beams in the plane of the drawing board and are such that the vertical beam can span a relatively wide board without intermediate rollers or other supports which would tend to mar a drawing being made.

45 As also has been previously mentioned, the rail beams are preferably made of extruded aluminum alloy, and in order to reduce the possibility of distortions occurring in the beams subsequent to their manufacture, machining operations thereon are maintained at a minimum. To this end, the only parts of the rail beams shown which are machined are the straight tracks or guideways along opposite sides of the narrow flange 22. Since this flange is in the form of a relatively low central projection on the web of the beam, its accuracy is maintained even though the narrow sides thereof are machined. The outwardly projecting flanges on the lower edges of the beams, in addition to adding stability, provide a convenient connection for clamping the beams to the work table of the machine during the machining operation of the longitudinal guideways on the flange 22 in a manner which will not stress the beams in a way which might cause inaccuracies.

50 Although the preferred embodiment of the invention has been described in considerable detail, the invention is not limited to the particular construction shown and it is the intention to hereby cover all adaptations, modifications and uses thereof which come within the practice of those skilled in the art to which the invention relates and within the scope of the appended claims.

Having thus described my invention, I claim:

5 1. In a drafting machine of the character referred to: a relatively wide, flat rail member having a first longitudinally extending guide surface at one side of its longitudinal center line and a second longitudinally extending guide surface at the other side of its longitudinal center line; said guide surfaces being on the same side of said rail member, angularly disposed to the plane of said rail member, opposed to one another and spaced from the longitudinal center line of said rail member less than the distance that they are spaced from the side edges of said rail member; a carriage adapted to have a drafting instrument operatively connected thereto; means connecting said carriage to said rail member for movement therealong; said means comprising a pair of rollers in engagement with said first guide surface; means connecting one of said rollers of said pair to said carriage for adjustment relative to the other roller of said pair transversely of the length of said rail member; means releasably securing said one roller of said pair of rollers in adjusted position; a third roller connected to said carriage and in engagement with said second guide surface; and means for effecting relative adjustment between both of said rollers of said pair of rollers in engagement with said first guide surface and said third roller in engagement with said second guide surface transversely of the length of said rail member.

2. In a drafting machine of the character referred to, a rail member having a relatively wide web portion provided with a pair of longitudinally extending transversely spaced opposed guide surfaces at opposite sides of its longitudinal center line, said guide surfaces being disposed at an angle to the plane of said web and spaced from the longitudinal center line thereof less than the distance that they are spaced from the side edges of said rail member, a carriage adapted to have a drafting instrument operatively connected thereto, means connecting said carriage to said rail member for movement therealong, said means comprising a pair of rollers connected to said carriage and in engagement with one of said guide surfaces at one side of said center line of said rail member and a third roller connected to said carriage and in engagement with the other of said guide surfaces at the other side of said center line of said rail member, means for adjusting one of said rollers of said pair of rollers relative to the other roller of said pair in a direction transversely of the length of said rail member, means for releasably securing said one roller of said pair in adjusted position, and means for moving said third roller relative to said carriage in a direction transversely of the length of said rail member.

3. In a drafting machine of the character referred to, a rail member comprising a relatively wide web portion provided with a pair of longitudinally extending transversely spaced opposed guide surfaces at opposite sides of its longitudinal centerline disposed at an angle to the plane of said web portion and supplemental guide surfaces adjacent to opposite side edges of said rail member, said guide surfaces of said pair being spaced from the longitudinal center line of said web portion less than the distance that they are spaced from the side edges of said rail member, a carriage adapted to have a drafting instrument operatively connected thereto, a pair of rollers in engagement with one of said pair of guide surfaces and connected to said carriage for adjustment relative to one another transversely of said rail member, means for releasably securing said rollers in adjusted position, a third roller in engagement with the other of said pair of guide surfaces and connected to said carriage for movement transversely of said rail member, and means on said carriage in engagement with said supplemental guide surfaces adjacent to the side edges of said rail member.

4. In a drafting machine of the character referred to, a rail member having a relatively wide web portion provided with a pair of longitudinally extending transversely spaced guide surfaces at opposite sides of the longitudinal centerline of the web portion and extending normal to the

plane of said web portion and supplemental longitudinally extending guide surfaces adjacent to the side edges of said member disposed at an angle to said first guide surfaces, said guide surfaces of said pair being spaced from the longitudinal center line of said web portion less than the distance that they are spaced from the side edges of said rail member, a carriage adapted to have a drafting instrument operatively connected thereto, a pair of rollers in engagement with one of said pair of guide surfaces and connected to said carriage for relative adjustment with respect to one another transversely of said rail member, means for releasably securing said rollers in adjusted position, a third roller in engagement with the other of said pair of guide surfaces and connected to said carriage for movement transversely of said rail member, and means on said carriage engaging said supplemental, guide surfaces.

5. In a drafting machine of the character referred to, a rail member having a relatively wide web portion provided on one side with a pair of longitudinally extending transversely spaced opposed main guide surfaces at opposite sides of the longitudinal centerline of the web portion and disposed at an angle to the plane of said web portion and supplemental longitudinally extending guide surfaces at opposite sides of both edge portions of said rail member disposed at an angle other than 90° to the plane of said web portion, said main guide surfaces being spaced from the longitudinal center line of said web portion of said rail member less than the distance that they are spaced from the side edges of said rail member, a carriage adapted to have a drafting instrument operatively connected thereto, a pair of rollers in engagement with one main guide surface of said pair of main guide surfaces and connected to said carriage for relative adjustment with respect to one another transversely of said rail member, means for releasably securing said rollers in adjusted position, a third roller in engagement with the other of said main guide surfaces of said pair of main guide surfaces and connected to said carriage for movement transversely of said rail member, means on said carriage engaging said supplemental guide surfaces on said one side of said rail member, counterweight means movably supported on said supplemental guide surfaces on the other side of said rail member, and means extending around the top end of said rail member connecting said carriage and said counterweight means.

6. In a drafting machine of the character referred to, a first respectively wide flat rail member having longitudinally extending transversely spaced guide surfaces at opposite sides of its longitudinal centerline and angularly disposed to the plane thereof, said guide surfaces of said first rail member being spaced from the longitudinal center line thereof less than the distance that they are spaced from the side edges of said first rail member, a first carriage, means connecting said first carriage to said first rail member comprising a first pair of rollers in engagement with one of said guide surfaces of said pair of guide surfaces on said first rail member and connected to said first carriage for movement transversely of said first rail member, means for releasably securing said first pair of rollers in adjusted position, a second relatively wide flat rail member having longitudinally extending transversely spaced guide surfaces at opposite sides of its longitudinal centerline and angularly disposed to the plane of said second rail member, said guide surfaces of said second rail member being spaced from the longitudinal center line thereof less than the distance that they are spaced from the side edges of said second rail member, means for pivotally connecting said second rail member to said first carriage for movement about an axis extending lengthwise of said first rail member, a second carriage adapted to have a drafting in-

strument operatively connected thereto, means connecting said second carriage to said second rail member comprising a second pair of rollers in engagement with one of said guide surfaces of said pair of guide surfaces on said second rail member and connected to said second carriage for relative adjustment with respect to one another transversely of said second rail member means for releasably securing said second pair of rollers in adjusted position, and a sixth roller in engagement with the other of said guide surfaces of said pair of guide surfaces on said second rail member and connected to said second carriage for movement transversely of said second rail member.

7. In a drafting machine of the character referred to, a first rail member having a relatively wide web portion provided with a pair of longitudinally extending transversely spaced main guide surfaces at opposite sides of the longitudinal centerline of the web portion of said first rail member and disposed at an angle to the plane of said web portion of said first rail member and supplemental longitudinally extending guide surfaces adjacent to the side edges of said first rail member disposed at an angle other than 90° to the plane of said web portion of said first rail member, said main guide surfaces of said first rail member being spaced from the longitudinal center line thereof less than the distance that they are spaced from the side edges of said first rail member, a first carriage, a first pair of rollers in engagement with one of said main guide surfaces of said pair of main guide surfaces on said first rail member and connected to said first carriage for relative adjustment with respect to one another transversely of said first rail member, means for releasably securing said first pair of rollers in adjusted position, a third roller in engagement with the other of said main guide surface of said pair of main guide surfaces on said first rail member and connected to said first carriage for adjustment transversely of said first rail member, means for releasably securing said third roller in adjusted position, means on said first carriage engaging said supplemental guide surfaces on said first rail member, a second rail member having a relatively wide web portion provided with a pair of longitudinally extending transversely spaced main guide surfaces at opposite sides of the longitudinal centerline of the web portion of said second rail member and disposed at an angle to the plane of said web portion of said second rail member and supplemental longitudinally extending guide surfaces adjacent to the side edges of said second rail member disposed at an angle other than 90° to the plane of said web portion of said second rail member, said main guide surfaces of said second rail member being spaced from the longitudinal center line thereof less than the distance that they are spaced from the side edges of said second rail member, a second carriage adapted to have a drafting instrument operatively connected thereto, a second pair of rollers in engagement with one of said pair of main guide surfaces on said second carriage and connected to said second carriage for relative adjustment with respect to one another transversely of said second rail member, means for releasably securing said second pair of rollers in adjusted position, a sixth roller in engagement with the other of said pair of main guide surfaces on said second carriage and connected to said second carriage for adjustment transversely of said second rail member, means for releasably securing said sixth roller in adjusted position, and means on said second carriage engaging said supplemental guide surfaces on said second rail member.

8. In a drafting machine of the character referred to a first rail member having a cross sectional shape resembling that of an I-beam, said first rail member having on one side a pair of longitudinally extending transversely spaced guide surfaces at opposite sides of the longitudinal centerline of its web and disposed at right angles to the plane of said web portion and supplemental guide surfaces along both edge portions thereof and disposed at an angle to said pair of guide surfaces, said guide surfaces of said pair being spaced from the longitudinal center line of said web

portion less than the distance that they are spaced from the side edges of said first rail member, a first carriage, a first pair of rollers in engagement with one of said guide surfaces of said pair of guide surfaces on said first rail member and connected to said first said carriage for relative adjustment with respect to one another transversely of the length of said first rail member, means for releasably securing said first pair of rollers in adjusted position, a third roller in engagement with the other of said guide surfaces of said pair of guide surfaces on said first rail member and connected to said first carriage for adjustment transversely of said first rail member, means for releasably securing said third roller in adjusted position, means on said first carriage engaging said supplemental guide surfaces on said first rail member, a second rail member having a cross sectional shape resembling that of an I-beam, said second rail member having on one side a pair of longitudinally extending transversely spaced guide surfaces at opposite sides of the longitudinal centerline of its web and disposed at right angles to the plane of said web portion and supplemental longitudinally extending guide surfaces on opposite sides of both edge portions of said second rail member angularly disposed to the plane of said pair of guide surfaces on said second rail member, said guide surfaces of said pair being spaced from the longitudinal centerline of said web portion less than the distance that they are spaced from the side edges of said second rail member, means for pivotally connecting one end of said second rail member to said first carriage for movement about an axis lengthwise of said first rail member, a second carriage adapted to have a drafting instrument operatively connected thereto, a second pair of rollers in engagement with one of said guide surfaces of said pair of guide surfaces on said second member and connected to said carriage for relative adjustment with respect to one another transversely of said rail member, means for releasably securing said second pair of rollers in adjusted position, a sixth roller in engagement with the other guide surface of said pair of guide surfaces on said second rail member and connected to said second carriage for adjustment transversely of said second rail member, means for releasably securing said sixth roller in adjusted position, means on said second carriage engaging said supplemental guide surfaces on the side of said second rail member upon which said pair of guide surfaces is located, counterweight means movably supported on said guide surfaces on the other side of said second rail member, means extending around opposite ends of said second rail member connecting said second carriage and said counterweight means.

9. In a drafting machine of the character referred to a relatively wide, flat rail member having longitudinally ex-

tending opposed guide surfaces spaced with respect to one another transversely of the rail member a distance less than one-fourth the width of the rail member, said guide surfaces being angularly disposed with respect to the plane of said rail member, a carriage adapted to have a drafting instrument operatively connected thereto, means connecting said carriage to said rail member for movement therealong, said means comprising a pair of rollers connected to said carriage and in engagement with one of said guide surfaces, means for adjusting one of said rollers of said pair of rollers relative to the other roller of said pair in a direction transversely of the length of said rail member, means for releasably securing said roller in adjusted position, a third roller connected to said carriage and in engagement with the other of said guide surfaces, and means for moving said third roller relative to said carriage in a direction transversely of the length of said rail member.

10. In a drafting machine of the character referred to a relatively wide, flat rail member having longitudinally extending opposed guide surfaces spaced with respect to one another transversely of the rail member a distance less than one-fourth the width of the rail member, said guide surfaces being angularly disposed with respect to the plane of said rail member, said rail member also having supplemental guide surfaces adjacent to opposite side edges thereof, a carriage adapted to have a drafting instrument operatively connected thereto, means connecting said carriage to said rail member for movement therealong, said means comprising a pair of rollers connected to said carriage and in engagement with one of said guide surfaces, means for adjusting one of said rollers of said pair of rollers relative to the other roller of said pair in a direction transversely of the length of said rail member, means for releasably securing said roller in adjusted position, a third roller connected to said carriage and in engagement with the other of said guide surfaces, means for moving said third roller relative to said carriage in a direction transversely of the length of said rail member, and means on said carriage engaging said supplemental guide surfaces.
